UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

MINING MACHINE

Application filed June 8, 1928, Serial No. 644,164. Renewed April 18, 1929.

The present invention relates to certain new and useful improvements in mining machines, and particularly to that class of mining machine which is provided with a main frame adapted to rest upon and slide in any direction over the mine floor, an elongated horizontally extending cutter arm attached to said frame, and means to move and guide said main frame over the mine floor to cause the cutter arm to engage the coal to cut it.

The especial object of this invention is to provide, in a machine of the class described, improved feeding and guiding mechanism whereby the machine may be moved over the mine floor at the speed most appropriate to the purpose intended.

The preferred embodiment of my invention is disclosed in the following specification and illustrated in the accompanying drawings of which—

Fig. 1 is a plan view of the machine the cover plates being removed and certain parts broken away to reveal other parts.

Fig. 2 is a side elevation of the machine illustrated in Fig. 1.

Fig. 3 is a somewhat diagrammatic horizontal sectional view showing the arrangement of gearing in the machine illustrated in Figs. 1 and 2.

Fig. 4 is a vertical sectional view taken along the line IV—IV of Fig. 1.

Fig. 5 is a vertical sectional view taken along the line V—V of Fig. 1.

Fig. 6 is a diagrammatic end view of the clutch shifting mechanism associated with the high speed winding drum.

Fig. 7 is a diagrammatic plan view of the devices illustrated in Fig. 6.

Fig. 8 is a sectional view taken along the line VIII—VIII of Fig. 3.

Figs. 9 and 10 are diagrams illustrating one of the methods of operating my improved mining machine in a mine room.

Like numerals refer to similar parts in the several figures.

Referring to the drawings the numeral 1 indicates the main frame casting upon which the operative parts of the machine are mounted. This main frame casting is attached to the upwardly turned flanges 2 of the skid pan

3 which is composed of rolled steel plate, and which serves as a broad supporting base adapted to rest upon and slide in any direction over the floor of the mine. Attached to the main frame casting 1, and projecting longitudinally thereof, is an elongated cutter arm 4, of well known construction, having guideways wherein travels the cutter chain 5 in the manner common to mining machines of this type. The cutter chain 5 engages and is actuated by a sprocket wheel 6 rotatively mounted upon the vertical shaft 7 which is rigidly attached to the main frame of the machine. Suitable clutch mechanism is provided by which the sprocket wheel 6 may be connected with the power devices of the machine. Mounted upon the main frame 1 is a motor 8 which may be of any preferred construction suitable to the conditions under which the machine operates. For purposes of illustration I have shown an electric motor having an armature shaft 9 to which is secured the bevel pinion 10. The pinion 10 engages a master gear 11 rigidly connected with a sleeve 12 mounted upon the vertical shaft 7, and this sleeve 12 constitutes the driving member from which the several elements of the machine are actuated. As all of these devices are well understood in the mining machine art, and as they form no part in the present invention, further description of them at this time is not thought to be required.

Formed upon the sleeve 12 is a worm 13 which engages a worm wheel 14 keyed to the horizontal power shaft 15 which is journaled in bearings 16 and 17 formed in the main frame casting 1. Mounted upon the power shaft 15, and connectable thereto by a suitable friction clutch, is a spur pinion 18 which meshes with a spur gear 19 of the feeding mechanism gear train. This friction clutch is preferably of the well known multiple disc type consisting of a driving member 20 keyed to the shaft 15, and a driven member 21 attached to the extension sleeve 22 of the pinion 18. These driving and driven members are connectable together by the friction discs 23 which are adapted to be pressed together by the pressure plate 24 to produce the friction necessary to transmit power for the actu-

ation of the spur pinion 18. Attached to the clutch member 21 by any suitable means, is a circular cover plate 25 which entirely encloses the mechanism of the clutch. A pressure screw 26 is threaded through the plate 25, and its inner end impinges upon the pressure plate 24. To the outer end of the screw 26 is fixed a hand wheel 27 by the manipulation of which the screw 26 may be rotated relative to the cover plate 25 to vary the pressure upon the discs 23, and thereby control the actuation of the clutch.

The feeding mechanism comprises a winding drum 28 to which is attached one end of the feed rope 29 which is adapted to be wound upon said drum. The free end of the rope 29 is adapted to be attached to a suitable abutment, external of the machine, towards which the machine will be drawn when the rope is wound upon the drum. The drum 28 is freely rotatable upon the sleeve 30 which, in turn, is eccentrically journaled upon the stud shaft 31 fixed to the main frame of the machine. Formed on the inner surface of the drum 28 is an internal gear 32 adapted to engage a spur pinion 33 which is attached to the outer end of a counter shaft 34. The counter shaft 34 is journaled in suitable bearings 35 of the machine frame, and to its inner end is attached the hereinbefore described spur gear 19 from which it receives power from the motor 8, through the drive connections already set forth for the actuation of winding drum 28. To the eccentric sleeve 30 is fixed a rocker arm 36 by which said sleeve may be rotated about the stud 31, and, due to the eccentricity of its support, such rotation will move the internal gear 32 into engagement with the pinion 33 to actuate the winding drum, or will move said gear out of such engagement to permit the free rotation of said winding drum in either direction. The rocker arm 36 is provided with a spring pressed latch 37 adapted to engage suitable apertures in the stud shaft 31 to hold the sleeve 30 in the preferred position of angular adjustment.

Mounted upon the power shaft 15 is a second friction clutch comprising the driving member 38 keyed to the shaft 15, and a driven member 39 adapted to be connected thereto by a plurality of friction discs 40 in the manner well understood in the art. A pressure plate 41 freely mounted concentrically upon the shaft 15 is arranged to contact with the outer disc of this series, and this pressure plate is engaged by a plurality of pressure rods 42 extending longitudinally of the shaft 15. The pressure rods 42 abut against a ball bearing thrust collar 43 carried by the screw nut 44, and the screw nut 44 is threaded to a sleeved extension 45 of the driven member 39 of the clutch. Formed on the periphery of the nut 44 is a spur gear 46 which engages with a gear wheel 47 fixed to the control shaft 48. The control shaft 48 is supported in suit-

able journal bearings of the main frame, and is provided with a hand wheel 49 in position convenient to the hand of the operator. By the manipulation of the hand wheel 49 the nut 44 may be rotated relative to the sleeve 45 to cause it to move longitudinally thereof to vary the pressure of the rods 42 upon the pressure plate 41, and thereby control the actuation of the clutch.

Freely rotatable upon the shaft 15, adjacent the last described friction clutch, is a hub 50 having a radially extending flange 51 on the outer edge of which is formed a winding drum 52, known as the handling drum. Attached to and windable upon the handling drum 52 is a handling rope 53 adapted to be carried around suitable guide sheaves upon the machine frame, to extend in any direction therefrom, and to be connected to a suitable abutment external of the machine, towards which the machine may be drawn by the winding of the rope 53 upon the drum 52. Longitudinally slidably upon the hub 50 is a collar 54 to which is attached the clutch pin 55. These pins 55 extend through apertures in the flange 51 and are adapted to engage with suitable apertures in the driven clutch member 39, constituting a pin clutch to positively connect the handling drum 52 therewith. Movement of the collar 54 longitudinally of said hub is effected by a forked shifting lever 56 pivoted upon a stud bolt 57 secured to the machine frame, and having lugs 58 which extend into the groove 59 formed in the collar 54. A notch 60 formed in the shifting lever 56, engages the crank pin 61 at the lower end of the rocker shaft 62, and a handle 63 formed on the upper end of the shaft 62, affords convenient means for the rotation of said shaft to shift the clutch pins 55 into and out of engagement with the clutch member 39.

Formed on the periphery of one of the flanges of the drum 52 is a spur gear 64 adapted to engage with a spur pinion 65 formed on the end of the counter shaft 66. To the opposite end of the counter shaft 66 is fixed a spur gear 67 adapted to engage with a spur pinion 68 formed on the extension sleeve 45 of the friction clutch. The counter shaft 66 is journaled eccentrically in the sleeve 69, and the sleeve 69 is rotatable in a journal bearing 70 formed on the machine frame. To the sleeve 69 is attached an arm 71 by which said sleeve may be rotated in its bearing, and a spring pressed latch 72, carried by the arm 71, is adapted to engagement with suitable apertures 73 in a flange 74 of the machine frame to hold said sleeve in the preferred position of angular adjustment. By the rotation of the sleeve 69 the counter shaft 66 will be moved towards or from the power shaft 15 to cause the engagement or disengagement of the gears 64, 65, 67, and 68.

Formed on the shifting lever 56 is an ex-

5 tension arm 75 which projects in the direction of the counter shaft 66, and on the end of the arm 75 is formed a key lug 76 in alignment with a keyway 77 cut transversely of the sleeve 69. The proportions of these parts are such that when the clutch pins 55 are in the engaged position the key lug 76 will project into the key way 77 to prevent rotation of the sleeve 69 thereby holding the counter shaft 10 gears out of engagement. When the clutch pins 55 are in their disengaged position, the sleeve 69 will be free to rotate to throw the counter shaft gears into engagement. When the counter shaft gears are in engagement 15 contact of the key lug 76 with the periphery of the sleeve 69 will prevent movement of the clutch pins 55 towards their engaged position. By this arrangement of parts the simultaneous engagement of the counter shaft 20 gears and pin clutch is effectively prevented.

In one operation of the machine it may be positioned upon the floor of the mine room adjacent the right hand rib wall, with the cutter arm projecting towards the coal face as 25 illustrated in Fig. 9. The rope 29 is then drawn out from the winding drum 28, passed around the guide sheave 78 at the left hand outer corner of the machine, and attached to a suitable anchor jack 79 positioned adjacent 30 the coal face at the left hand side of the room. The rope 53 is then drawn out from the handling drum 52, passed around the guide sheave 80 at the right hand outer corner of the machine, and attached to a suitable anchor 35 jack 81 positioned adjacent the right hand rib near the coal face. The cutter chain 5 is then actuated, and the clutch mechanism associated with the winding drum 28 adjusted to permit a slippage of the friction disc sufficient 40 to hold the winding drum 28 against rotation in the unwinding direction. The clutch pins 55 are then shifted to their disengaged position, the counter shaft 66 shifted to cause the engagement of the low speed 45 gears. By the manipulation of the hand wheel 49 the friction clutch will transmit power to the winding drum 52 to wind the rope 53 and thrust the cutter arm 4 longitudinally into the coal, to form the sumping or 50 entering cut. After the machine is fully sumped the rope 29 is removed from the guide sheave 78 and passed around the sheave 82 at the left hand inner corner of the machine frame; after which the hand wheel 27 is manipulated to cause the discs in the friction 55 clutch to actuate the winding drum 28 to wind the rope 29 and draw the machine laterally towards the anchor jack 79 to cut a kerf across the coal face. The hand wheel 49 is at the same time manipulated to permit a slippage of the clutch discs 40 sufficient to permit 60 the unwinding of the rope 53 against a frictional resistance which maintains the angular relation of the machine to the coal face.

65 After the completion of the kerf the ma-

chine will be moved to a point convenient for loading upon its truck for transportation to the next working place. The feed rope 29 is disconnected from the anchor jack 79, and the clutch mechanism manipulated to discontinue the actuation of the drum 28. The low speed gears of the handling drum 52 are then thrown out of engagement, the clutch pins 55 thrown into engagement, and the rope 53 attached to a jack 83 placed conveniently near the loading position, as illustrated in Fig. 10. By the manipulation of the hand wheel 49 the winding drum 52 will be actuated to draw the machine towards the loading position.

70 For efficient operation the various movements of the machine should be executed as quickly as conditions will permit, and the proportions of the gearing above described are such as to produce traveling speeds proportionate to the resistance encountered.

75 While working laterally across the coalface the entire side of the cutter arm is in contact with the coal, producing a maximum resistance to the advance of the machine. The gearing through which the winding drum 28 is actuated is so proportioned that said drum will revolve at a relatively low speed, which in practice is commonly about eighteen inches per minute, although under favorable conditions this rate is sometimes made as high as two feet or two feet and a half per minute.

80 While the cutter arm is being thrust longitudinally into the coal, to form the sumping cut, only its end is in effective contact with the coal and the resistance to such movement is proportionately less than during lateral operation. The low speed gearing through which the handling drum 52 is actuated to perform the sumping or entering cut, is so proportioned that the machine will be advanced at about double the speed of lateral cutting. In practice this speed is approximately three feet per minute, although under favorable conditions the machine may be adapted to cut as fast as four or five feet per minute.

85 While moving the idle machine about the floor of the mine, to or from operative position, the resistance to such movement is relatively small, and when the handling drum 52 is connected directly with the power shaft 15 through the agency of the pin clutch 55, the rope 53 will be wound at a relatively high speed, which in practice ranges from eighteen to twenty five feet per minute.

90 By this arrangement of gearing the machine may be moved over the floor of the mine at a relatively low speed for lateral cutting, at an intermediate speed for sumping, and at a relatively high speed for handling, thereby 100 affecting greatly increased efficiency of operation.

105 What I claim is:—

110 1. In a machine of the class described, the combination with a main frame adapted to

rest upon and slide in any direction over the mine floor, of an elongated kerf cutter projecting horizontally from said main frame, power devices upon the main frame adapted to actuate the kerf cutter, a flexible draft member adapted to be connected with a suitable abutment external of the machine, winding means upon the machine adapted to exert strain upon said draft member to move the machine towards said abutment at a relatively low speed, a second flexible draft member adapted to be connected with a suitable abutment external of the machine, winding means upon the machine adapted to exert strains upon the last mentioned draft member to move the machine towards the last mentioned abutment, a high speed connection between said power devices and the winding means for said second draft member, an intermediate speed connection between said power devices and the winding means for said second draft member, and means for rendering either of said connections active as and for the purpose set forth.

2. In a machine of the class described, the combination with a main frame adapted to rest upon and slide in any direction over the mine floor, of an elongated kerf cutter projecting horizontally from said main frame, power devices upon the main frame adapted to actuate the kerf cutter, a flexible draft member adapted to be connected with a suitable abutment external of the machine, winding means upon the machine adapted to exert strain upon said draft member to move the machine towards said abutment at a relatively low speed or to resist its movement from said abutment, a second flexible draft member adapted to be connected with a suitable abutment external of the machine, winding means upon the machine adapted to exert strain upon the second draft member to move the machine towards the last mentioned abutment, a high speed connection between said power devices and the winding means for said second draft member, an intermediate speed connection between said power devices and the winding means for said second draft member, and manually operable means for rendering either of said connections active as and for the purpose set forth.

3. In a machine of the class described, the combination with a main frame adapted to rest upon and slide in any direction over the mine floor, of an elongated kerf cutter projecting horizontally from said main frame, power devices upon said main frame adapted to actuate the several elements of the machine, a flexible draft member adapted to be connected with a suitable abutment external of the machine, means to exert strains upon said draft member to move the machine towards said abutment at a relatively low speed, a second flexible draft member adapted to be connected with a suitable abutment ex-

ternal of the machine, means to exert strain upon the last mentioned draft member to move the machine towards the last mentioned abutment, a high speed connection between said power devices and the strain exerting means for the second draft member, an intermediate speed connection between said power devices and the strain exerting means for the second draft member, and manually operable means for rendering either of said connections active as and for the purpose set forth.

4. In a machine of the class described, the combination of a main frame, a power shaft mounted on said frame, a winding drum, a gear connection between said power shaft and said drum, means for controlling the operation of said gear connection, means to control transmission of power from said power shaft to said gear connection, a second winding drum, a gear connection from said power shaft to said second drum, a second drive connection from said power shaft to said second winding drum and means for locking in disconnected position one of the connections with said second drum upon connecting the other.

5. In a machine of the class described, the combination of a main frame, a power shaft on said frame, a winding drum having a gear, a driving gear operable from said power shaft to engage said drum gear, means for controlling the co-operation of said gears, manually operable means to control transmission of power from said power shaft to said drum driving gear, a second winding drum having a gear, a gear connection between said power shaft and said drum gear, a second driving connection between said power shaft and said second drum and means for locking in disconnected position said second driving connection upon the operation of said gear connection.

6. In a machine of the class described, the combination of a main frame, a power shaft on said frame, a winding drum having a gear, a driving gear operable from said power shaft to engage said drum gear, means for controlling the engagement of said gears, manually operable means to control transmission of power from said power shaft to said drum driving gear, a second winding drum having a gear, a gear connection between said power shaft and said drum gear, a manually operable second driving connection between said power shaft and said second drum and means for locking in disconnected position one of the driving connections to said second winding drum upon connecting the other.

7. In a machine of the class described, the combination of a main frame, a power shaft mounted on said frame, a winding drum having a gear, a gear connection between said power shaft and said drum, means for controlling the engagement of said winding

drum gear with said gear connection, a friction clutch to control transmission of power from said power shaft to said driving gear, a second winding drum, a gear connection between said second winding drum and said power shaft, a direct connection between said winding drum and said power shaft and means for locking in disconnected position said direct connection upon the actuation of the gear connection to said second winding drum.

8. In a machine of the class described, the combination of a main frame, a power shaft disposed transversely of the frame, a winding drum having a gear, a driving gear connecting said power shaft and said drum means for controlling the cooperation of said winding drum gear with said driving gear, a manually operable friction clutch mounted at one end of said power shaft to connect said shaft and said driving gear, a second winding drum having a gear, a driving gear connection between said power shaft and said second drum, means for shifting said second driving gear from active to inactive position, a manually operable friction clutch for directly connecting said power shaft and said second drum, and means controlling the driving connections between said power shaft and said second drum, whereby one of said driving connections is held inactive when the other is in active position.

9. In a machine of the class described, the combination of a main frame, a power shaft disposed transversely of the frame, a winding drum having an eccentrically mounted gear, a driving gear adapted to connect said power shaft and said drum, means for shifting said eccentrically mounted drum gear from active to inactive position, a manually operable friction clutch mounted at one end of said power shaft to connect said shaft and said driving gear, a second winding drum having a gear, an eccentrically mounted driving gear connection between said power shaft and said second drum, means for shifting said eccentrically mounted second driving gear from active to inactive position, a manually operable friction clutch for directly connecting said power shaft and said second drum, and means controlling the driving connections between said power shaft and said second drum whereby one of said driving connections is held inactive when the other is in active position.

In testimony whereof I have hereunto set my hand.

NILS D. LEVIN.
